UNITED STATES PATENT OFFICE.

JOHN H. SMITH, OF GLIDE, OREGON.

MANUAL-POWER MACHINE.

SPECIFICATION forming part of Letters Patent No. 625,475, dated May 23, 1899.

Application filed July 13, 1898. Serial No. 685,863. (No model.)

To all whom it may concern:

Be it known that I, JOHN H. SMITH, a citizen of the United States, residing at Glide, in the county of Douglas and State of Oregon, 5 have invented certain new and useful Improvements in Manual-Power Machines; and I do hereby declare the following to be a full, clear, and exact description of the invention, such as will enable others skilled in the art to 10 which it appertains to make and use the same.

This invention relates to manual-power machines or windlasses adapted for moving heavy bodies, such as houses, pulling stumps, or elevating and lowering weights of various 15 character; and it consists, essentially, of a support having in one side thereof an operating-wheel connected to a drum upon which a rope is adapted to wind or be unwound therefrom, hand-levers being located on opposite sides of the wheel with engaging devices for turning the same, and a brake at the upper part for limiting the movement, particularly in elevating or lowering heavy bodies.

25 The invention further consists of the details of construction and arrangement of the several parts, which will be more fully hereinafter described and claimed.

The object of the invention is to provide a 30 machine wherein the expenditure of manual power through the medium of hand-levers will be decreased and controllable at all times to facilitate the movement of heavy bodies or displacement of resisting forces either in horizontal or vertical planes.

In the accompanying drawings, Figure 1 is 35 a side elevation of the improved machine. Fig. 2 is a section through the same. Fig. 3 is an end elevation thereof. Fig. 4 is a top plan view.

40 Referring to the drawings, wherein similar numerals of reference are employed to indicate corresponding parts in the several views, the numeral 1 designates the side sills of a base 2, which are connected by end cross-ties

45 3. Rising from the center of the sills are standards 4, connected by a cap-beam 5, and journaled in the said standards at a suitable elevation is a shaft 6, having a square portion 7, on which is mounted a drum 8, and connected to the drum or relatively coacting therewith is a wheel 9. The standards 4 are

supported by opposite oblique braces 10, and running from one of the standards to the cap 5 is an upper brace 11. Thus it will be seen 55 that the parts are all thoroughly braced and reinforced to provide stable support for the working mechanism and also to resist the straining tension incident to moving heavy objects.

60 The wheel 9 is composed of two oppositely-situated rims 12, having considerable width and connected by bolts 13, on which space-sleeves 14 are mounted to hold the said rims at a proper distance apart from each other. 65 Extending inwardly from each rim are flat spokes 15, which are regularly arranged, and connected to the outer portion of each is the outer end of a tangential brace 16, which has its opposite end running to and firmly secured 70 to the inner portion of an adjacent spoke. This mode of bracing the spokes is continued throughout the whole series and in each rim, and crushing or fracture of said spokes is thereby prevented. The inner ends of the 75 spokes 15 connect by suitable means with a central hub 17, and the strain by arrangement of the tangential braces 16 is equally divided or distributed on all the spokes.

80 A rock-shaft 18 is pivotally mounted in the sills 1 adjacent one end of the base 2, and firmly secured thereto is the inner end of a hand-lever 19, having a slot 20 near said inner end thereof, in which is pivotally mounted the lower end of an elongated curved catch-pawl 21, having an engaging head 22 at its upper end. The said head 22 has a concave 85 engaging edge 23 to adapt it to pass over the space-sleeves 14 on the bolts 13, and at the lower portion of said head a shoulder 24 is 90 formed to drop over the said space-sleeves for the purpose of rotating the wheel 9 in a manner which will be presently set forth. The distance between the space-sleeves and the 95 dimensions of the head 22 are proportioned relatively in order that the said head may properly operate with the said sleeves.

On the opposite end of the base 2 and rising from the cross-tie 3 is a fulcrum-post 25, which is slotted at its upper end to pivotally receive a second hand-lever 26. The inner end of this hand-lever 26 is also slotted, and therein is pivotally mounted the lower end of a push-pawl 27, having an upper head 28, with

a concave engaging surface 29 to bear against the adjacent under portions of the sleeves 14 in succession, and thereby increase the power necessary to rotate the wheel 9. The head 28 at one side extends upwardly a greater distance, as at 30, so as to always insure an engagement with the sleeves 14, and the inner edge of the pawl is curved in such manner as to easily ride over the successive sleeves in taking a new hold. To retain the push-pawl in proper engagement with the several sleeves, a spring 31 is secured to the lever 26 and bears against the said pawl. Secured to the end of the said cap 5, adjacent to one of the standards 4, is a transverse support 32, having its opposite end slotted, as at 33 and 34, and pivotally mounted in the slotted end 34 is a gravitating pawl 35, which has a lower broadened end 36, adapted to automatically drop over the successive sleeves 14 and prevent backward movement of the wheel 9, while the levers 19 and 26 are operated to cause their pawls to change position, and thereby avoid release or slack of the cable, which is wound on the drum 8 and attached to the object being moved. In the slotted end 33 of the said transverse support a brake-lever 37 is pivoted and provided with a lower brake-shoe 38, which is brought to bear upon the peripheries of the wheel-rims 12. Connected to the upper end of the brake-lever 37 is a link 39, which is in turn movably attached to the outer end of an operating-lever 40, pivotally mounted in a fulcrum-block 41, secured on top of the cap 5.

In operating the wheel the levers 19 and 26 are grasped and the former elevated to raise the pawl 21 and cause the shoulder 24 of the head 22 thereof to take over the sleeve 14 and bolt 13 next above, and to attain this operation the said lever 19 is elevated and afterward depressed to draw the wheel 9 around. At the same time or independently, as may be found desirable, a downward pressure is exerted on the lever 26, which forces the pawl 27 upwardly to its full stroke and afterward elevated to cause the head 28 of the pawl 27 to take hold of the next lower sleeve 14 and bolt 13. By working these levers and pawls simultaneously the applied power is increased, and it will be seen that the pawl 27 at all times engages the sleeves 14 and the bolts 13 therein at a plane below the point of engagement of the head 22 of the pawl 21. As the wheel is revolved by the said pawls 21 and 27 the drum 8 is rotated and the cable wound thereon when a drawing power is de-

sired. During the rotation of the wheel 9 the gravitating pawl 35 automatically operates to sustain the adjustment and is positioned at such an angle as to make it impossible for an overthrow thereof or disengagement from the sleeves and bolts. As an additional protection against accident the brake-lever 37 may be operated at any time to check the loose movement of the wheel 9, and which is accomplished through the operating-lever 40. This brake attachment, however, is particularly adapted for use when the machine is employed for elevating or lowering heavy weights, and, if desired, at times the general position of the machine might be changed to accommodate the work done or to be done.

By the arrangement of levers as set forth, in connection with the wheel 9, a strong pulling power can be exerted and utilized for various purposes, and owing to the compactness and comparative simplicity of the mechanism the machine may be easily transported from one place to another without inconvenience and is always ready for operation.

Of course additional appurtenances—such as blocks, guys, and the like—may be used with the machine to facilitate its operation, and changes in the proportions, dimensions, and minor details of construction might be resorted to without departing from the nature or spirit of the invention or sacrificing any of the advantages thereof.

Having thus described the invention, what is claimed as new is—

In a machine of the character set forth, the combination of a frame having a base, a shaft having a square portion, a drum mounted on said square portion of the shaft and having a wheel attached thereto provided with a circumferential space between parts thereof and cross connections with intervening openings, a rock-shaft on the base of the frame, a hand-lever attached to said rock-shaft, an elongated pull-pawl attached to said lever and adapted to engage the connections of the wheel, an opposite hand-lever carrying a push-pawl to engage said connections, a brake-lever having a shoe located above the wheel and adapted to engage an upper part of the latter, and an upper gravitating-pawl to engage the connections of the wheel.

In testimony whereof I affix my signature in presence of two witnesses.

JOHN H. SMITH.
